UNITED STATES PATENT OFFICE.

WALTER HILLIER ANDERSON, OF LONDON, ENGLAND.

CINEMATOGRAPH APPARATUS.

1,168,993.

Specification of Letters Patent.

Patented Jan. 18, 1916.

Application filed March 5, 1915. Serial No. 12,461.

To all whom it may concern:

Be it known that I, WALTER HILLIER ANDERSON, a subject of the King of Great Britain and Ireland, and residing at 5 den House, Phoenix street, London, N. W., England, have invented certain new and useful Improvements in and Relating to Cinematograph Apparatus, of which the following is a specification.

10 This invention relates to cinematograph apparatus and more particularly to the arrangement for masking the pictures.

When starting a new picture it generally happens that the film has not been placed 15 upon the sprocket wheels so that the picture correctly registers with the aperture in film gate and more or less of the top or bottom of the picture is exhibited upon the screen. To overcome this it is necessary to provide 20 means for raising or lowering the Maltese cross without it turning upon its center; otherwise the pictures would continue to be displayed out of register with the shutter.

It is usual in cinematograph machines to 25 work the Maltese cross gearing through a train of wheels comprising firstly an intermediate wheel which is actuated by the main driving mechanism and whose axle is mounted in the bush of the rocking member. 30 member which carries the cam and Maltese cross wheels, which bush constitutes the turning center of the rocking member in the main frame. The intermediate wheel gears with a second wheel adapted to move in a vertical 35 guide in the rocking member, while this latter wheel engages the wheel in axial connection with the cam wheel, the necessary adjusting motion of the rocking member being obtained by means of levers and links, 40 whereby the slide carrying the second wheel is given a movement which provides the differential action required.

The object of the present invention is to 45 provide an improved means for adjusting the film which is simple in construction, has fewer parts and is more efficient, whereby the said system of linkages is dispensed with and the second wheel is given a rotary movement from a center fixed in relation to the 50 main frame while remaining in the correct engagement with the cam gear wheel.

The invention consists broadly in mounting the second wheel upon a radius arm one end of which turns about a pivot on the 55 main frame while the other end is supported by and moves with the axle of the

cam wheel whereby the axle of the second or differential wheel follows a radial movement when masking of the picture is being effected.

60 The accompanying drawings illustrate by way of example the preferred method of carrying the invention into effect, in which;

Figure 1 is a side elevation of a cinematographic apparatus embodying the present 65 invention. Fig. 2 is a front elevation of the mechanism. Fig. 3 is a sectional plan along the line A—B of Fig. 2.

In this illustrated embodiment of the invention 70 1 represents the axle of the driving wheel 2, the axle being bushed in the rocking member 3 which carries the Maltese cross wheel 4.

Upon the rocking member 3 is a bush 5 through which passes the axle 6 carrying the 75 cam wheel 7 which gears with the Maltese cross or star wheel 4. The bush 5 constitutes the fulcrum of a radius arm 8 whose outer end is slotted at 9. Within the slot is a pin or pivot 10 which is riveted to or otherwise secured to the bracket 11, which bracket is fixed to the main frame 12 of the apparatus. On the radius arm 8 is a stud 18 carrying a second toothed or differential wheel 13 gearing with the two toothed 80 wheels 2 and 15, the former being mounted on the driving shaft while the latter is secured to the axle 6 which carries the cam wheel 7. For convenience of assembling, the cam and star wheels are incased within 85 a chamber 14 which is formed by a recess in the rocking member and the cover plate 16, an inspection window 17 being provided as shown in front of the star wheel.

The gearing from toothed wheel 2 to the 90 star wheel 4 may be called the star wheel train.

The rocking arm 8 is maintained in its position upon the boss 5 by the set screw 20 working in a groove or by other suitable 100 means.

The axle 19 of the star wheel 4 is carried by two bushings in the rocking member 3 and between these supports is arranged the sprocket wheel 21 which draws the film 105 through the gate of the apparatus.

The action of the mechanism is as follows: Upon starting the apparatus, should the film not be correctly masked, the rocking member 3 is rotated about the center 1, 110 within the opening 26 of the main frame 12 by means of the handle 22 which is centered

friction tight at 23, the opposite end 24 being connected by the link 25 to a convenient position on the member 3. By lowering the handle 22 link 25 is moved upward; this movement raises the boss end 5 of the radius arm 8 which turns about the pivot 10. The result of the pivot 10 being arranged where shown is that the same teeth of the toothed wheels 2 and 13 remain in gear during the masking, presuming for the time being that the driving wheel 2 is at rest. Hence the cam 7 and the star wheel 4 do not move relatively to the rocking member 3, and the film is caught up later if the member 3 rises and sooner if the member 3 is lowered, whereby the masking or registration of the film with the opening in the shutter of the apparatus is effected.

It is to be understood that various modifications of the above mechanism are possible without departing from the general principle of the invention.

Having now described my invention, what I claim as new and desire to secure by Letters Patent is:—

A mechanism for the masking or registration of the film with the opening in the

shutter of a cinematograph machine, comprising in combination a main frame member, a driving wheel axle, a wheel thereon, a shutter with opening operated through the medium of said axle, a cam shaft, a cam wheel thereon, a Maltese cross gearing with said cam wheel, a rocking member pivoted on the main frame at the said driving wheel axle, a radius arm carried by the shaft of the cam wheel, a bracket secured to the main frame, a pin or pivot fixed in the said bracket and engaging with the outer end of the radius arm, a pinion on the cam wheel shaft, and a differential wheel pivoted on the radius arm which engages both the driving wheel and the said pinion whereby the film is caught up sooner or later as the rocking member is reciprocated, the masking being thereby effected.

In testimony whereof I have signed my name to this specification in the presence of two subscribing witnesses.

WALTER HILLIER ANDERSON.
